LAMP GUARD HANDLE

Hugh B. Gould, Berwyn, Ill., assignor by mesne assignments, to Francis C. Kollath, Chicago, Ill.

Application May 29, 1946, Serial No. 130,228

Term of patent 14 years

(Cl. D48—24)

To all whom it may concern:

Be it known that I, Hugh B. Gould, a citizen of the United States, residing at Berwyn, Cook County, Illinois, have invented a new, original, and ornamental Design for a Lamp Guard Handle, of which the following is a specification, reference being had to the accompanying drawings forming a part thereof:

Fig. 1 is an elevational view of a lamp guard handle, showing my new design, the opposite side being substantially the same as the side shown;

Fig. 2 is an end view of the right end of Fig. 1;
Fig. 3 is an end view of the left end of Fig. 1.

I claim:

The ornamental design for a lamp guard handle, as shown and described.

HUGH B. GOULD.
